CHARLES J. PEMBROKE, OF ROCHESTER, NEW YORK.

CARBURETER.

1,055,352.

Specification of Letters Patent. Patented Mar. 11, 1913.

Application filed August 9, 1911. Serial No. 643,243.

To all whom it may concern:

Be it known that I, CHARLES J. PEMBROKE, of Rochester, in the county of Monroe and State of New York, have invented certain new and useful Improvements in Carbureters; and I do hereby declare the following to be a full, clear, and exact description of the same, reference being had to the accompanying drawings, forming a part of the specification, and to the reference-numerals marked thereon.

My present invention relates to carbureters for use in conjunction with explosive engines and has for its object to provide a device of this character capable of automatically controlling the quantity of the fuel oil, or gasoline, and the pressure of the air supply admitted to the engine or motor under all the various conditions of operation.

My invention has for its further object to provide a carbureter with an additional fuel discharging device for supplying to the engine the proper quantity of volatile oil or fuel to form the charge when such is required as a means of starting the engine under certain atmospheric conditions.

To these and other ends the invention consists in certain improvements and combinations of parts all as will be hereinafter more fully described, the novel features being pointed out in the claims at the end of the specification.

In the drawings: Figure 1 is a vertical sectional view showing a carbureter constructed in accordance with my invention; Fig. 2 is a horizontal sectional view taken on the line 2^x-2^x of Fig. 1; Fig. 3 is a detail perspective view of the pressure controlling member or sleeve; Fig. 4 is a detail vertical sectional view on the line 4^x-4^x of Fig. 2; and Fig. 5 is a view similar to Fig. 3 illustrating a modified arrangement of the parts.

Similar reference numerals through the several figures indicate the same parts.

In the illustrations adopted to illustrate one embodiment of my invention, I have shown a carbureter comprising a casing composed of upper and lower sections 1 and 2, within which are the centrally arranged vaporizing and carbureting chambers. The chamber in the upper section is formed by

the wall 3 curving inwardly at the top, communicating with the passage 4, which, it will be understood, is connected directly with the intake pipe or manifold of a gas engine. The carbureting chamber is formed by the annular wall 5, the upper end of which projects through the bottom of the chamber 1, where it is provided with a plurality of apertures 6 which are preferably made V-shaped so as to form graduated openings which increase in area from their lower edges to the top of the wall. Above the latter and supported by the wall 3 is a partition 7 provided with a central aperture 8. In the casing 1 the upper portion of the vaporizing chamber is surrounded by the chamber 9 to opposite sides of which lead intake and outlet pipes 10 and 11 which are preferably connected in the water circulating system of the motor with which the carbureter is to be used, for the purpose of maintaining the latter in a warmed or heated condition. Arranged in the passage 4 is the usual butterfly throttle valve 12. The lower section 2 of the casing also constitutes the float chamber 13 containing the volatile oil or fuel, the latter being fed thereto from a suitable source of supply through the passage 14 controlled by the valve 15, which is opened and closed by the float 16, connected to the valve by the pivoted crank arm 17, said valve and crank arm being disposed in a laterally protruding portion 18 of the float chamber.

The gasoline or fuel oil is supplied to the carbureting chamber and introduced into the latter through the nozzle 19 provided with a perforation or outlet 20, the flow of oil therefrom which is constant during the operation of the engine being determined by the needle valve 21. In the present instance the nozzle 19 is disposed centrally within the carbureting chamber projecting therein the desired distance from a laterally extending arm or support 22 having a passage 23 leading to the valve seat of the needle valve. This arm is connected to the casing 2 by a bolt 24 provided with a passage 25, which opens communication between the fuel chamber and the passage 23. Surrounding and integral with the lower end of the nozzle at a suitable distance below the lower edge

of the wall 5 is a disk 26 on which rests the pressure regulating member or sleeve. The latter comprises the collar 27, the body 29 provided with the central air passage and the top plate 30. The upper portion of the collar projects into the bottom of the air intake passage, its lower end normally resting upon the disk 26, the inner edge of the collar and the edge of the disk being preferably beveled, as shown, and the edge of the disk being provided with notches or serrations 28. The body of the member or sleeve comprises the hollow frustum-conoidal portion forming a restricted neck 29, the walls of which are perforated, as shown, the inner surfaces thereof converging from the top of the collar 27 to a point in proximity to the end of the nozzle or inlet port 20 forming a restricted air passage α in the member. At the top of the latter is a horizontally extending top plate or disk 30, the whole member being of such a length that when in its normal position the disk is supported in the position shown in Fig. 1, in proximity to the lower ends of the graduated apertures 6 at the top of the wall 5.

In practice the total area of the niches 28 in the disk 26 are made approximately equal to the area of the passage α of the pressure regulating or controlling member, and the graduated openings 6 are made of such a size that when these are uncovered by the elevation of the pressure controlled member to its highest point, as indicated in Fig. 3, their combined areas, with the area of the passage α , will approximately equal the area of the throttle controlled passage 4. The shape and configuration of the apertures in the side wall of the restricted portion of the pressure controlled member may be formed as desired, but their combined areas should be at least equal to, and preferably slightly greater than the combined areas of the graduated openings 6, and at the same time provide a surface which combined with the under surface of the disk 30, will afford a sufficient resistance to the inrushing air to permit the member to be automatically operated by the strong inrush of air currents which exists in the inlet passage when the engine is operated at high speeds, and to maintain an air cushion on which the sleeve rides at such times. The sleeve works vertically, gravitating to its normal position at low engine speed and rises and falls with the fluctuations in the pressure of the inrushing air occurring upon changes of engine speed, the use of springs or other mechanical devices for effecting the movement of the pressure regulated member being eliminated.

In carrying out my invention in the form illustrated as one embodiment thereof, I

form the central opening α of the pressure regulating member on such lines that as the sleeve is carried upwardly or automatically adjusted longitudinally of the intake passage, the cross sectional area of the opening α in the plane or zone of the discharge port 20, increases to control the force of the suction exerted at this point as desired.

The control of the gasoline or fuel is accomplished by the formation of the tapered inner surface of the passage α of the pressure controlling member, which, when in its normal lowermost position causes the maximum suction force to be created at the gasoline outlet when the engine is being started. As the speed of the latter increases, by the opening of the throttle valve 12, the inrushing air drawn through the vaporizing chamber or intake creates a pressure causing the movable member or sleeve to rise and in so doing the disk 30 opens the graduated openings 6, more or less, to establish a balanced condition of the member or sleeve. Upon the upward movement of the latter it will be noticed that the area of the passage α , in the plane of the gasoline outlet 20, is increased to regulate the suction at this point so that only that amount of gasoline is drawn into the engine which is sufficient to provide a proper carbureted mixture with the increased air supply then being drawn into the engine. It will be noticed by this arrangement of the parts that the pressure regulating member simultaneously controls the air inlet ports and the feed of gasoline into the vaporizing chamber.

In Fig. 5 I have shown a modified arrangement of the graduated air passages. In this arrangement of the apparatus, the top portion of the tubular wall 5 is omitted, said wall terminating in the annular horizontal plate 50. The pressure controlling member top plate or disk 300 is provided with a depending flange having the inverted V-shaped graduated apertures 60. Upon the vertical movement of the member or sleeve the depending flange rises and falls relatively to the plate 50 to control the size of the air openings formed by the apertures 60.

The arrangement of the apertures or openings in the intake passage and the movable member or sleeve may be varied from the form shown, and these parts may be otherwise arranged without departing from the spirit of my invention, but in practice a distinct advantage is found to exist in arranging the openings practically as illustrated, since in addition to rendering the carburetor automatic in its operation, they also serve to produce a very thorough admixture of the vaporized liquid and air.

I have also applied to my carburetor an

additional fuel supply reservoir adapted to be used when an exceptionally rich mixture is required for starting the engine.

At one side of the casing 2 I provide an auxiliary chamber 4 communicating with the float chamber 13 through the passage 41 provided with a seat normally closed by the valve head 42 operated by the spring 43 and provided with a suitable operating device such as a wire 44, by means of which the valve may be retracted. The chamber 40 is preferably proportioned to hold the required amount of gasoline which, flowing into the chamber at the level of the liquid in the float chamber, will provide the proper amount of fuel required to enrich the charge sufficiently for starting the engine under the most unfavorable conditions. Leading from the bottom of the chamber is an outlet suction pipe 45, the opposite extremity 46 of which is introduced into the passage 4 of the carburetor at a point above the throttle valve 12. In the event the operator has difficulty in starting his engine, an inconvenience which is especially experienced in cold weather, he may retract the valve head 42 permitting the chamber 40 to receive its supply of gasoline which will be immediately drawn into the engine cylinders by the suction produced by the cranking operation, provided the throttle is in a nearly closed condition. The engine starting by this enriched charge will subsequently draw through the vaporizing chamber the required mixture to continue its operation.

I claim as my invention:

1. A carburetor comprising a single cylindrical air intake passage, a liquid fuel inlet nozzle discharging into said passage, and a movable member in the passage comprising a perforated tapered sleeve normally restricting but not completely closing the area of the passage, and which is automatically adjusted by the pressure of the air passing through said intake to increase the least cross sectional area of the intake, said member also coöperating with the fuel inlet, the tapered wall of the sleeve and the perforations therein, serving upon movement of the member to vary the suction force created at the zone of the inlet by the air traveling through the intake passage.

2. A carburetor for forming explosive mixtures for explosive engines comprising a casing, provided with an intake passage for air having an outlet for the carbureted mixture adapted to be connected to an engine cylinder and a fuel supply inlet nozzle discharging into the intake passage, of a gravity operated sleeve having a perforated tapered body portion surrounding the inlet and adapted to be moved longitudinally in the intake passage by the inrushing air to

control the pressure of air in and permit different quantities of air to pass through 65 said intake and also vary the suction produced at the zone of the fuel inlet.

3. In a carburetor, the combination with a casing having a vaporizing chamber provided with a tubular air inlet passage and 70 a wall projecting beyond the inlet into the chamber and provided with graduated openings, of a sleeve movable in the air inlet and coöperating with said openings, said sleeve having an air passage leading there-through a portion of which is provided with converging walls, and a fuel discharge inlet opening into said air passage of the sleeve.

4. In a carburetor, the combination with a 80 casing having a chambered portion and a tubular portion opening therein having a wall projecting into the chamber and provided with apertures, of a pressure regulating member movable longitudinally in 85 the intake comprising a disk coöperating with the apertures in the wall to open and close them and a portion below the disk provided with a conoidal shaped air passage, and a fuel inlet discharging into said air passage.

5. In a carburetor, the combination with a casing having an air intake passage provided with inlet apertures, of a member movable longitudinally in the intake comprising a part coöperating with the apertures to open and close them and a hollow frusto-conoidal shaped portion provided with perforations in its side walls and forming a longitudinally extending air passage 100 through the member, and a fuel inlet discharging into said air passage.

6. In a carburetor, the combination with a casing having an air intake passage, comprising a chambered portion and a wall extending thereinto having inlet passages, and a fuel supply inlet projecting into said intake, of a member movable longitudinally in the latter having a hollow tapered portion forming an air passage surrounding the fuel inlet and provided with perforations in its walls, and a top part normally lying below the inlet passages in said wall to cut off communication between said chamber and the intake passage excepting through the air passage in said member and adapted upon movement of the member to open communication between the chamber and intake through said inlet passages.

7. In a carburetor, the combination with 120 a casing having a chamber and a vertically arranged air inlet leading into the chamber and comprising a free wall surrounding the inlet and projecting into the chamber and provided with a plurality of apertures 125 increasing in area toward the top of the

4
wall, of a gravity operated member in the inlet having a top plate closing the intake below said apertures and a perforated tubular portion forming an air inlet passage normally connecting the outer end of the intake with the chamber, said member being adapted to be automatically adjusted by the inrushing air to open communication

between the intake and the chamber through said wall apertures and a fuel inlet leading into the air inlet passage of the member.
